SOCKET FOR ELECTRIC LAMPS

Joseph Wertzheiser, Bronx, N. Y., assignor to
 Leviton Manufacturing Company, Brooklyn,
 N. Y., a corporation of New York

Application March 17, 1937, Serial No. 131,233

1 Claim. (Cl. 173—354)

This invention relates to a lamp socket that can be enclosed in the standard caps and shells. This lamp socket embodies a switch mechanism that can be operated by a pull chain or other 5 switch operating mechanism to open and close the circuit through the lamp.

The invention will be understood from the description in connection with the accompanying drawings, in which Fig. 1 is a side view of 10 an illustrative embodiment of the invention; Fig. 2 is a section along the line 2—2 of Fig. 1; Fig. 3 is a section at right angles to Fig. 2; Fig. 4 is a section along the line 4—4 of Fig. 3; Fig. 5 is a section along the line 5—5 of Fig. 3; Fig. 6 is 15 a plan view of the lower side of one of the members of the socket; Fig. 7 is a section somewhat similar to Fig. 4 but showing other parts and also omitting some parts; Fig. 8 is a section along the line 8—8 of Fig. 3; Fig. 9 is a plan view of 20 the make and break member; Fig. 10 is a perspective view of the same; and Fig. 11 is a side view at right angles to Fig. 1.

In the drawings, reference character 10 indicates a screw shell of the usual sort for a lamp 25 bulb (not shown). Fiber disks 12 and 13 are attached to the upper end of the shell 10 by screws 14 and 15 (Figs. 2, 3 and 4) which extend into threaded openings 16 and 17 respectively in the line terminals 18 and 20.

30 The line terminal 18 is provided with a binding screw 19 for one side of the line, this terminal 18 being kept in place by the screw 14. The other terminal 20 for the other side of the line is provided with a binding screw 21 and is kept in place by the screw 15. The screw shell 10 is provided with the usual slot 22 (Figs. 1 and 3) at the bottom and adjacent sides.

A horn 23 is provided with a grooved plate 23' (Figs. 1, 3, 4, 5, 7 and 11) by means of which it 40 is held in place and a pull chain 24 having an enlarged bead 24', to prevent accidental displacement of the chain, passes through the horn 23 for operating the switch mechanism to be described. The horn 23 is held in place by its plate 23' being clamped between the fiber disk 13 and a thick disk 25 (Figs. 1, 3, 5 and 11) that may be made of porcelain or other insulating material. Projections 26 along the lower edge of the plate 23' extend into openings 27 provided 45 therefor in the disk 13 and a projection 28 on the upper edge of the plate 23 extends into an opening 28' in the lower side of the disk 25.

An arcuate recess 29 (Figs. 1, 3, 6 and 11) extends along the lower edge of the disk 25. 50 Axially extending recesses 30 and 31 (Figs. 2 and

6) are provided along the edges of the disk 25 and are aligned with the terminals 18 and 20, respectively, so that lead wires can be attached to these terminals by passing them through these recesses inside of the usual shell that encloses 5 the socket. Notches 32 and 33 are provided in the disk 25 at the lower ends of the recesses 30 and 31 to accommodate the ends of the line terminals 18 and 20 respectively. An integral extension 34 (Figs. 3, 6 and 11) is provided along 10 the lower side of the disk 25 near its edge but off set toward the center from the recess 29. The plate 23' of the horn rests against this extension 34.

A circular opening 35 (Figs. 2, 3 and 6) is provided in the lower side of the disk 25 and a small hole 36 is provided at the center of this opening. An opening 37 extends through the disk 25 and is provided with a countersink 38 at its upper end. A screw bolt 39 extends through holes in 15 the bottom of the shell 10, aligned holes in the disks 12 and 13, and the hole 37 in the disk 25, and clamps the parts together on a three point support for the disk 25 consisting of plate 23' and line terminals 18 and 20, the bolt 39 lying 20 inside of a circle passing through these three supports. The bolt 39 screws into a square nut 39' in the square countersink 38.

A plurality of projections 40 (Fig. 1) are formed on the bottom of the screw shell 10 made 25 by indenting the metal from the inside and these projections extend into corresponding openings 41 provided in the disk 12 to prevent the shell 10 and disk 13 from being accidentally turned 30 with respect to each other.

A center spring contact 42 (Figs. 1, 2, 3, 4, 7, 8 and 11) of thin metal is attached to the disk 13 by means of the rivet 43 and has a portion thereof 40 extending through a hole 44 in the disk 13 and terminating in an arcuate contact portion 45 which slopes upwardly in an anti-clockwise 40 direction as viewed from the upper end of the socket or as viewed in Figs. 4, 7 and 8. The extremity or exit end of this portion 45 for a switch rests upon a solid portion of the disk 13. One edge of the disk 12 (Fig. 2) is cut away, as shown at 46, to accommodate the center contact 42 and an opening 47 is provided in this disk 12 for passage of the head of the screw 15 so that this disk 12 can be easily slipped into place.

One end 48 (Figs. 2, 7 and 8) of a thin switch contact member is fastened to the bottom of the disk 13 by the head of the screw 15. This switch contact member passes through an arcuate opening 49 in the disk 13 and its switch contact end 50

50 is similar to the contact end 45 with one end thereof resting upon a solid portion of this disk. It is spaced 180° from the contact end 45.

A shaft 51 (Figs. 2, 3 and 4) for the switch mechanism passes through a hole 52 in the disk 13 and fits snugly in this hole. The enlarged flat head 53 of the shaft 51 is securely clamped between the disks 12 and 13 so that the shaft 51 is prevented from turning or being pulled to the side. The disks 12 and 13 are sufficiently flexible so that they can be brought into close contact with each other even with a portion of the center contact 42, the end of the contact member 48 and the flat head 53 located between them.

15 The upper end of the shaft 51 extends loosely into the hole 36 in the disk 35, but the shaft remains firmly held in place with its head 53 clamped between the disks 12 and 13 even when the disk 25 is removed. The shaft 51 is reduced 20 in size and made square near one end, as indicated at 54 to accommodate a bifurcated stop 55 for the spring 56. This bifurcated stop is slipped on the flattened portion of this shaft from the side and can be used for adjusting the tension 25 of the spring. A lug or catch 57 is provided on the stop 55 for the end 56' of the spring 56. The other end 56'' (Figs. 3, 4, 7 and 8) of this spring extends into a hole 58 in a switch operating lever 59 that is formed from a flat piece of fiber that 30 is provided with a hole by means of which this lever is journaled on the shaft 52 and is permitted to move up and down on this shaft as this spring 56 is compressed and expands. A metal link 60 connects the outer end of the lever 59 to 35 the pull chain 24.

A switch closing member 61 (Figs. 2, 3, 9 and 10) is revolvably mounted on the shaft 51. It is provided with oppositely disposed bent down contact arms 62. These contact arms are provided 40 with elongated sloping ends 63 for contacting with the sloping ends 45 and 50 of the contacts 42 and 48. Oppositely disposed struck up tongues 64 (Figs. 9 and 10) are provided on the side of the switch member between the arms 62. Four 45 equally spaced openings 65 (Figs. 4 and 7) are provided in the lever 59 surrounding the shaft 51. The ends of the tongues 64 catch against the edges of the openings 65 when the switch lever 59 is turned in one direction, but this lever rides over 50 these tongues when it turns in the other direc-

tion, due to the fact that the spring 56 yields. Oppositely spaced openings 67 and 68 (Fig. 8) are provided in the disk 13 between the openings 44 and 49, so that the edges of these four openings provide stops in four positions for preventing the switch member 61 from being turned backwards.

The operation is as follows:

The parts are shown in the circuit closing position in Fig. 2, the current passing from the terminal 20, screw 15, contact member 48, circuit closing member 61 and its arm 62, center contact member 42, the lamp (not shown), shell 10, screw 14 (Fig. 3), to the other terminal 18. In this position of the switch 61, the ends of the sloping portions 63 of the arm 62 prevent the switch from being turned backwards. When the pull chain is pulled, the lever 59 turns the switch 61 in an anti-clockwise direction (Figs. 4 and 7), thus causing the contact portions 63 of the arm 62 to drop into the openings 67 and 68 between the ones in which the contacts 44 and 50 are located, thus breaking the circuit. When the pull chain is released the spring 56 returns this lever 59 to the position where its edge contacts with the terminal 18, during which time this lever rides over the tongues 64 so that these tongues snap into the next pair of openings 65 in this lever. The next pull of the chain 24 turns the switch member 61 another quarter revolution, thus again closing the switch.

I claim:

In a lamp socket, a base and a cap both of insulating material and spaced apart, said base being formed of two non-frangible disks, a shaft 35 extending between said base and cap and having one end loosely received in a recess in said cap and having the other end extending through one of said disks, an enlarged head on said shaft disposed between the disks, means securing said 40 disks together in clamping contact with opposite sides of said head to hold the shaft against rotation or reciprocation in respect to the base, means securing said base and cap together in spaced relation and with said first-named end 45 of the shaft in said recess, and a switch mechanism in said space, part of said mechanism being rotatably supported on said shaft.
